Specification for Design.

Patented Oct. 17, 1916.

Application filed July 20, 1916. Serial No. 110,410. Term of patent 14 years.

To all whom it may concern:

Be it known that we, WILLIAM S. VORIS and VICTOR A. PARKER, citizens of the United States, residing at Akron, in the county of Summit and State of Ohio, have invented a new, original, and ornamental Design for Tire-Treads, of which the following is a specification, reference being had to the accompanying drawings, forming a part thereof.

In the drawings, Figure 1 represents a top plan view, and Fig. 2 a cross-section of a portion of a tire showing our novel tread design.

We claim:

The ornamental design for a tire tread as shown.

WILLIAM S. VORIS.
VICTOR A. PARKER.
